United States Patent

[19]

Smith et al.**Patent Number: Des. 427,964****Date of Patent: ** Jul. 11, 2000****[54] ELECTROCHEMICAL CELL****[75] Inventors: Ian L. Smith; John Fawcett**, both of New York, N.Y.**[73] Assignee: Eveready Battery Company, Inc., St. Louis, Mo.****[**] Term: 14 Years****[21] Appl. No.: 29/109,834****[22] Filed: Aug. 23, 1999****[51] LOC (7) Cl. 13-02****[52] U.S. Cl. D13/103****[58] Field of Search D13/103; 429/96-100, 429/159, 167, 174, 101; D9/519, 549; D23/205****[56] References Cited****U.S. PATENT DOCUMENTS**
